CLAIM

The ornamental design for a multi-fiber optical connector with housing for optical connector, as shown and described.

DESCRIPTION

FIG. 1 is a front view of a multi-fiber optical connector with housing for optical connector showing our new design; FIG. 2 is a rear view thereof; FIG. 3 is a right side view thereof, the left side view being a mirror image thereto; FIG. 4 is a top plan view thereof; FIG. 5 is a bottom view thereof; FIG. 6 is a sectional view taken along lines 5-5 in FIG. 1; FIG. 7 is a perspective view thereof; and, FIG. 8 is a reference perspective view showing the multi-fiber optical connector with housing for optical connector shown in FIG. 1 in a state of use. The broken lines depict environmental subject matter only and form no part of the claimed design.
